(57) **CLAIM**

The ornamental design for a kitchen utensil handle, as shown and described.

DESCRIPTION

FIG. 1 is a perspective view of a kitchen utensil handle according to my new design;

FIG. 2 is a rear view thereof;

FIG. 3 is a left side view thereof, with the right side being a mirror image thereof;

FIG. 4 is a front view thereof;

FIG. 5 is a cross sectional view taken along line 5—5 of FIG. 2;

FIG. 6 is a cross sectional view taken along line 6—6 of FIG. 2;

FIG. 7 is a perspective view of a second embodiment of a kitchen utensil handle according to my new design;

FIG. 8 is a rear view thereof;

FIG. 9 is a left view thereof, with the right side being a mirror image thereof;

FIG. 10 is a front view thereof;

FIG. 11 is a cross sectional view taken along line 11—11 of FIG. 8; and,

FIG. 12 is a cross sectional view taken along line 12—12 of FIG. 8;

1 Claim, 4 Drawing Sheets
